UNITED STATES PATENT OFFICE.

KALM GRIFFITH RICKARDS, OF MOOREFIELD, NEBRASKA.

ELEVATING-TRUCK.

SPECIFICATION forming part of Letters Patent No. 674,471, dated May 21, 1901.

Application filed February 2, 1900. Serial No. 3,686. (No model.)

To all whom it may concern:

Be it known that I, KALM GRIFFITH RICKARDS, residing at Moorefield, in the county of Frontier and State of Nebraska, have invented certain useful Improvements in Elevating-Trucks; and I do hereby declare that the following is a full, clear, and exact description of the invention, such as will enable others skilled in the art to which it appertains to make and use the same, reference being had to the accompanying drawings, which form a part of this specification.

This invention relates to an improvement in portable elevators.

The object of my invention is to provide an elevator light and portable enough so that the same may be conveniently shoved from place to place, and is adapted to be used in loading barrels, bags, and other packages upon wagons.

In the accompanying drawings I have shown in Figure 1 an end elevation of a portable elevator embodying my invention, while Fig. 2 is a side view thereof.

As has been stated, the aim of my invention is more particularly to provide an elevator that shall be light and portable enough so as to be readily moved from place to place and so constructed that bags and barrels which would be too heavy for one man to lift into a wagon can be rolled upon the platform of my elevator and carried on a level with the wagon-bed and from thence rolled over into the wagon by one man. From this it will be seen that by means of my improved elevator one operator will be able to lift such loads as would require the assistance of two or three men were this appliance or a similar one not used.

My invention embodies a platform 5, preferably upon casters 20, to which is hinged a pair of uprights 1, which above are united by the cross-beam 2, reinforced by the stays 4.

To maintain the framework in an upright position while the elevator is being used, I provide the braces 6, which are secured to the upright by means of the hand-screws *c* and to the platform 5 by means of the hand-screws *c'*, so that the elevator in being carried through doors or when not in use may be folded down to occupy the least amount of space. A further great advantage is that

the platform, together with this framework, may be used as a truck, so that the bags, boxes, or barrels may be loaded upon the 55 platform 7 within the warehouse and then be pushed or dragged by means of this framework, operating like handles to a truck, to and adjacent to the wagon, where the frame is then thrown upright and secured, when the 60 platform is unloaded.

Secured within the upper end of the frame is an ordinary shaft 8, provided with the drums 9 and 10, which shaft is provided at the ends with the sprocket 21, over which passes an 65 ordinary chain 13, and secured to the drums or spools 9 and 10 are two ordinary cables 11 and 12, divided below, as shown in Fig. 2, so that the two ends *aa* may be suitably secured to the platform 7. This platform is of a suitable size and is provided upon the sides with the openings *x*, adapted to receive the pins *e e*, there being a number of these openings, and when these pins, which are really only necessary upon one side, are in position, the 75 platform is practically held in a horizontal position between the framework. At suitable points one of these uprights is further provided with a number of openings 19', into which an ordinary pin 19 is inserted, so that 80 the platform is solidly supported when resting upon this pin 19 within one of the openings.

Secured to the lower portion of the frame is the crank-operated sprocket 15, provided 85 with an integral ratchet acted upon by means of a pawl 14, so that the platform is further supported by means of this pawl and ratchet at points intermediate of the openings 19'. An ordinary chain 13 unites the upper sprocket 90 21 to this lower sprocket 15.

From this it will be noticed that I have constructed a wheel-supported portable elevator-carriage provided with an operating-frame by means of which the carriage may be drawn 95 or pushed, a platform working between the framework, and mechanism to raise and lower the platform.

While the platform is to be held in a horizontal position, the pins *e e* are to be placed 100 within the innermost pair of openings; but when the material is to be unloaded the pins are switched from this pair of openings into a pair farther from the upright, so that the

platform will be tilted at an angle. This tilting of the platform will enable the operator to readily slide off the boxes, barrels, or bags, and so materially aids in expediting the operation of unloading the elevator.

The device is noticeable because of its extreme simplicity.

Having thus described my said invention, what I claim as new, and desire to secure by 10 United States Letters Patent, is—

In an elevator of the character described, a portable platform, two united uprights hinged to said platform, mechanism to lock said uprights in a vertical position, a shaft

revolubly supported within the upper end of 15 said uprights, an elevator-platform depending from said shaft by means of suitable supporting-strands, a plurality of openings with in the side of said elevator-platform, a plurality of pins adjustable within said openings 20 to guide said platform, and a chain-sprocket provided with a pawl and ratchet and in chain connection with said upper shaft.

Signed in the presence of two witnesses.

KALM GRIFFITH RICKARDS.
